CLAIM

The ornamental design for an assembling toy, as shown and described.

DESCRIPTION

FIG. 1 is a front view of an assembling toy of the present invention, having separable male and female parts.

FIG. 2 is a rear view thereof.

FIG. 3 is a top plan view thereof.

FIG. 4 is a bottom plan view thereof.

FIG. 5 is a right side view thereof.

FIG. 6 is a left side view thereof.

FIG. 7 is a perspective view thereof.

FIG. 8 is a top plan view of the male part thereof.

FIG. 9 is a right side view of the male part thereof.

FIG. 10 is a perspective view of the male part thereof.

FIG. 11 is a left side view of the female part thereof.

FIG. 12 is a perspective view of the female part thereof.

FIG. 13 is a sectional view thereof taken along the line 13-13 of FIG. 5.

FIG. 14 is a sectional view thereof taken along the line 14-14 of FIG. 9.

FIG. 15 is a sectional view thereof taken along the line 15-15 of FIG. 9.

FIG. 16 is a sectional view thereof taken along the line 16-16 of FIG. 11; and,

FIG. 17 is a sectional view thereof taken along the line 17-17 of FIG. 11.

The alternate long and short dash lines indicate bounds of the claimed design and form no part thereof.

The features shown in broken lines are included to illustrate portions of the assembling toy and form no part of the claimed design.

1 Claim, 17 Drawing Sheets
